CLAIM

The ornamental design for a balloon support as shown and
described.

DESCRIPTION

FIG. 1 is an upper perspective view of a balloon support
according to a new design.

FIG. 2 is an enlarged perspective view of the balloon support
of FIG. 1 removed from environment for clarity of disclosure.

FIG. 3 is a left side view of the balloon support apparatus
shown in FIG. 1 shown removed from environment for
clarity of disclosure.

FIG. 4 is a right side view of the balloon support apparatus
shown in FIG. 1 shown removed from environment for
clarity of disclosure.

FIG. 5 is a front view of the balloon support apparatus
shown in FIG. 1 shown removed from environment for
clarity of disclosure; and,

FIG. 6 is a rear view of the balloon support apparatus shown
in FIG. 1 shown removed from environment for clarity of
disclosure.

The broken lines in the drawings depict portions of the
balloon support that form no part of the claimed design; the
additional broken lines shown in FIG. 1 are for environmental
purposes only and form no part thereof.

1 Claim, 4 Drawing Sheets
